JOHN H. WHITNEY, OF ROCHESTER, MINNESOTA.

Letters Patent No. 109,164, dated November 8, 1870.

IMPROVEMENT IN STOP-MOTION GEAR-WHEELS.

The Schedule referred to in these Letters Patent and making part of the same.

To all whom it may concern:

Be it known that I, JOHN H. WHITNEY, of Rochester, in the county of Olmstead and State of Minnesota, have invented certain Improvements in Stop-Motion Gear-Wheels, of which the following is a specification, reference being had to the accompanying drawing.

My invention relates to stop-gear wheels, for producing an intermittent motion of one by a continuous rotary motion of the other; and

The invention consists in the novel construction of the wheels, as hereinafter more fully explained.

Figure 1 is a side elevation of two wheels constructed on my plan.

Figure 2 is an edge view of the same.

In many kinds of machinery it is necessary to impart to certain motions an intermittent motion, and it is frequently desirable that the pinion or driven wheel should have a greater or lesser number of revolutions without changing the diameter of the wheels; and in all cases where this style of wheels is used it is specially desirable that the driven wheel or pinion should stop, and be held in an exact position, in order to permit the teeth of the driving-wheel to strike fair between the teeth of the pinion when the motion of the latter is to be renewed, to prevent breaking or injuring of the gear, and also to prevent the wheels from becoming locked by the striking together of the ends of the teeth. It is to accomplish these objects, and to furnish a more perfect gearing, that my invention is intended.

To accomplish these objects I construct my improved wheels as follows:

The driving-wheel A I make with teeth, on a portion of its periphery, more or less in extent, according to the size of the pinion to be driven and the number of revolutions it is to have.

Along the side of the wheel A, opposite that portion of it which has no teeth, I make a laterally-projecting flange, *e*, as shown in figs. 1 and 2, this flange being either cast solid with the wheel, or bolted to it, as preferred.

This flange *e* ceases at the point where the teeth begin, as shown in figs. 1 and 2.

The pinion B I make in the usual form, but to one side of it I attach a stop-plate, *c*, as shown in fig. 1.

This plate or projection *c* has one end extended out beyond the periphery of the teeth, and its end face is cut or formed concave, in the form of a segment of a circle, corresponding with the circumference of the driving-wheel A, or rather of the flange *e* thereon, as represented in fig. 1.

This outer or concave edge of the stop-plate *c* and the periphery of the guard-flange *e* being turned or

otherwise made smooth, so that the former may bear upon the latter, while the latter is in motion, without binding or catching thereon.

It will be seen that, when a pair of wheels thus made, is properly mounted, so as to gear together in the usual manner, the teeth of the wheel A will engage with those of the wheel B, and cause the latter to revolve until all the teeth on A have passed the end of the stop-plate *c*, rotating with the wheel B, will project down alongside of the teeth on A, as represented in fig. 2.

At the instant, however, that the teeth have all passed, the flange *e* will have arrived at a position where the end of the stop-plate *c* will strike upon it as the plate comes opposite, and will thus hold the pinion B stationary while the wheel A continues its movement.

As the teeth on wheel A come around and again engage with those of wheel B, the flange *e* will pass from under the stop-plate *c*, thus unlocking the pinion and permitting it to resume its motion.

The end of plate *c*, where it bears off the flange *e*, may be enlarged or made wider than represented in the drawing, so as to have a broader bearing thereon, if desired.

By this construction I am able to produce a very superior stop-motion gear, that will work with great accuracy and smoothness, and which obviates, to a great extent, the danger of breaking the teeth, or of locking them so as to stop the machinery.

It is obvious that the wheels may be made of any proportions desired, and that the teeth may be arranged to give more or less revolutions to the pinion, as required. It is also obvious that the teeth on wheel A, and also the flange *e* of the same, may be made in sections, so as to be bolted onto the wheel or removed therefrom at will, thus enabling it to be so changed as to increase or decrease the number of revolutions of the wheel B at pleasure.

Having thus described my invention,

What I claim is—

1. The wheel A, with the laterally-projecting flange *e*, in combination with the wheel B, having the stop-plate *c*, all constructed and arranged to operate substantially as described.

2. The wheel A, having its teeth and its flange *e* each formed in sections, so that the sections may be attached or detached at will, and thus vary the number of revolutions of wheel B, as described.

JOHN H. WHITNEY.
